HEAT EXCHANGER FOR LIQUIDS

Emil Behringer, Richmond Hill, N. Y.

Application April 25, 1933, Serial No. 667,843

12 Claims. (Cl. 257—206)

This invention relates to apparatus for exchanging the temperature of liquids and more particularly to means for cooling milk, as after pasteurizing, though it is noted that the invention is not limited to cooling nor to use for milk.

One object of the invention is to provide apparatus of this kind in which a large volume of milk or other liquid may be quickly cooled or heated.

Another object of the invention is to provide an apparatus or device of this kind in which all surfaces which come in contact with the milk may be made easily accessible for cleaning.

Another object of the invention is to provide an apparatus or device of this kind in which the parts may be quickly separated for cleaning and quickly reassembled for operation.

Other objects of the invention are to improve generally the simplicity and efficiency of such apparatus and to provide apparatus of this kind which is economical of construction, durable, reliable and sanitary in operation, and economical to clean, manufacture and install.

Still other objects of the invention will appear as the description proceeds; and while herein details of the invention are described in the specification and particularly pointed out in the claims, the invention is not limited to these, since many and various changes may be made without departing from the scope of the invention as claimed in the broader claims.

The inventive features for the accomplishment of these and other objects are shown herein in connection with an improved heat exchanger which, briefly stated, includes an inner and a pair of outer temperature exchanging or cold brine chambers detachably connected, and having side walls of meandering cross-section to form respectively laterally projecting chamber portions and deep recesses adapted to receive said projections and to form therewith a thin meandering passage space. A distributing supply and a discharge means for the milk communicate respectively with upper and lower parts of said space; while liquid inlet and discharge means for the brine connect to all the heat exchange chambers, being detachably connected to the outer chambers, so that the outer chambers and their supports may be removed, to expose all of the surfaces of said passage space for cleaning.

In the accompanying drawings showing, by way of example, one embodiment of the invention,

Fig. 1 is an end elevation showing the apparatus assembled;

Fig. 2 is a side elevation;

Fig. 3 is a fragmental end elevation showing

the parts on a larger scale, the outer brine chambers not being drawn into close contact with the central frame;

Fig. 4 is a fragmental side elevation of a corner of the apparatus;

Fig. 5 is a fragmental plan of one end of the apparatus, the parts not being drawn tightly together;

Fig. 6 is a fragmental transverse vertical sectional view on the line 6—6, of Fig. 2, partly in elevation, showing the chambers;

Fig. 7 is a fragmental longitudinal vertical sectional view, partly in elevation, showing the relation of said projections and recesses, the section being taken substantially on the off-set line 7—7 of Fig. 6, looking in the direction of the arrows of said line;

Fig. 8 is a fragmental side elevation, showing the upper header chamber and distributing means, the view being taken substantially from the line of 8—8 Fig. 6, looking in the direction of the arrows of said line; and

Figs. 9 and 10 are enlarged fragmental vertical sectional views showing parts of Figs. 6 and 7, showing more clearly the thin passage space, the section of Fig. 10 being taken substantially on the line 10—10 of Fig. 9, looking in the direction of the arrows of said line.

The principal parts of the apparatus will first be very briefly indicated, after which they will be described in detail.

A stationary support 10 (Fig. 1) carries a frame 15 comprising upper, lower and upright members, and in which is secured an inner brine chamber 23 (Fig. 6) secured between the upright frame members, and spaced from the upper and lower frame members to form header chambers 24 and 25 (Figs. 6 and 3) for the reception and discharge of the milk through pipes 63, 66 and 69. Inner chamber side walls 30 of meandering cross-section form laterally projecting chamber portions 31 (Fig. 6) received in recesses 54 of the outer flow chambers 40 detachably connected fluid-tight by means 56, 58 (Fig. 3) to the flanges 20 on each side of said frame 15. Each outer chamber has an inner wall 50 of meandering cross-section to form recesses 54 adapted to receive said projections 31 and to form a thin meandering milk passage 52 connecting said header chambers 24, 25. Inlet and discharge means 70, 73, 77 for cold brine are connected to inner chamber 23 and detachably connected to the outer chambers 40 by detaching means 85, 86, 88 (Fig. 5).

When said detaching means 56, 58, 85, and 88 are detached the outer chambers 40 may be rolled

on the wheels 36 (Fig. 1) to separate and expose the boundary walls of the milk passage 52 (Fig. 6) for easy flushing and cleaning with steam, hot water and suitable materials.

5 Now the parts will be described in detail.

An elongated inner pedestal support 10 having feet 11 and flat supporting heads 12 at the upper end, supports, in a vertical plane, an elongated rectangular frame 15 formed of an integral, rectangular channel frame and comprising a horizontal top 16, a horizontal bottom 17, and vertical ends 18 (Fig. 6) consisting each of a web perpendicular to said plane and flanges 20 on opposite edges of the web extended in a direction 15 away from the interior of the frame, said heads 12 being received between the flanges and against the web of the bottom of the frame.

A metallic, enclosed inner flow chamber housing, Fig. 6 made up in one piece, either cast or 20 welded, and generally denoted by 23, for carrying cold brine is comprised of top and bottom walls, 27 and 28, respectively; these latter walls form an upper header chamber 24, Fig. 6 and a lower header chamber 25, Fig. 3. Between the top 25 and bottom walls as viewed in Fig. 6 the flow chamber housing is convoluted into a zig-zag formation, the side walls 30 of the housing being angularly convoluted and being joined at their inner and outer ends by curves 31 and 31', as in 30 Figs. 9 and 6. These convolutions are closed on their sides by wall 29, Figs. 6 and 10, so that the flow housing is only open at ports 73—73 for purposes to later be described.

The housing 23 is mounted spaced midway between the top 16 and bottom 17 of frame 15 and in the interior thereof and is so held, by suitable attaching means not shown, between itself and the sides 18—18 of the frame 15.

A pair of elongated movable supports 35 (Figs. 40 1 and 2) having wheels 36 mounting the supports for lateral movement on tracks 37 having flanges 38 engaging said wheels guiding the movable supports into parallel cooperation with the inner support 10.

45 An outer flow chamber 40 (Figs. 2 and 6) mounted on each outer support comprises top and bottom walls 41, 42, outer side walls 43 and end walls 44 (Fig. 7), the bottom wall 42 resting on the support, the end walls 44 marginally projecting beyond the other walls as at 44a to form end flanges serving to help hold heat insulating material on the walls 41, 42, 43, as at 44b (Fig. 5). The top, bottom and end walls are outwardly turned at the inner edges to form securing flanges 45 (Figs. 5 and 6) adapted to be secured to adjacent respective flanges 20 of the frame 15.

The flanged margins 47 of the top and bottom walls 41, 42, are outwardly offset adjacent to the flange to form inner seats to receive inwardly turned upper and lower flanges 48 of the outer chamber heat-exchanging wall 50, the part between said flanges having a deeply meandering cross section cooperating with the end walls to form deep outwardly tapering recesses 51 adapted, when the securing flanges 45 are secured to the frame, to receive and almost, but not quite, contact the walls 30 of the inner brine chamber, thereby to form a thin meandering passage space 52, of extended wall surface, between the inner chamber of housing 23 and chamber 40, the said passage, connecting the header chambers 24, 25 (Figs. 6 and 3).

75 The outer face of the side walls 30 of the brine chamber are provided with spacing ribs 54 (Figs. 9 and 10) disposed parallel to the end

walls, for engagement with the adjacent heat exchanging walls 50 of the outer brine chambers to prevent restriction of the passage 52.

Means for detachably securing the flanges 20 and 45 together comprise H-blocks 55 (Fig. 4) pivoted at one end between flanges 20 of the frame, each having an outer transverse bore receiving clamping bolts 56 each provided with a head 57 and a wing-nut 58. Adjacent flanges of said frame and outer chambers are provided with deep bolt receiving notches 59, (Fig. 4) adapted to receive said bolts 57 whereby the adjacent flanges 20 and 45 with gaskets 60 therebetween may be clamped together in a fluid tight manner.

A liquid supply pipe 63 (Figs. 6 and 8) passing in a fluid tight manner through the top 16 of the frame and clamped to the web by a ring nut 64, is provided at its inner end with a T-connection 65 carrying perforated distributing pipes 66 having removable plugs 67 closing the outer ends. The pipes 66 are disposed along the header space to distribute the liquid entering through the supply pipe 63. A discharge pipe 69 (Fig. 6) passes through the mid part of the bottom 17, 25 whereby a stream of the liquid to be conditioned may be kept passing through the passage 52 in contact with the temperature-exchanging walls of the inner and outer chambers.

Lower and upper heat-exchange medium inlet 30 and discharge pipes 70, 71 (Fig. 3) extending to near one of the ends 18 near the lower and upper parts of the inner chamber end walls respectively carry four-way connectors 72 each secured to a stationary branch pipe 73 from one member of 35 the connector to the adjacent portion of the inner housing 23.

Each connector has oppositely disposed horizontal members 75 (Fig. 5) each provided with an end seat face 76 and aligned with movable 40 branch pipes 77 extending from the outer chambers through the upper and lower parts of the end wall of each outer chamber to near the respective end seats 76, and having free ends 78 adapted to be received in said seats. A clamping collar 80 secured on each free end portion engages a thick rubber gasket ring 81 disposed between the collar and adjacent seat 76. A bracket 83 on each 4-way connector has a bore parallel to the horizontal members 75 and carries loosely a clamping bolt 84 having a wing head 85 at one end and threads 86 at the other. Clamping jaws 88 on said bolt and engaged by the threads and head respectively are provided with lateral recesses 89 (Fig. 4) adapted to receive the pipes 77 to hold the jaws in engagement with said collars 80 whereby the collars 80, gaskets 81 and seats 76 may be detachably held together in a fluid tight manner.

Horizontal baffles 93, 94 (Fig. 6) disposed all the 60 way across said inner and outer chambers except at the extreme projecting portions of the heat exchange surface, serve to keep the stream of heat exchange medium in contact with the heat exchange surfaces.

Bolts 95 passing through the pedestal heads 12 and the lower flanges 20 hold the frame 15 in place and carry locating ring nuts or heads 96 received in recesses in the flange 45 for locating the outer chambers relative to the frame and 70 inner chamber.

The operation:

While the operation herein described is for cooling milk in the passage 52 (Fig. 9), with the milk moving downward therein and brine moving 75

upward in the chamber of housing 23 and chamber 40, it is understood that under certain circumstances it might be desirable to use other temperature exchanging liquids, and directions of flow of the liquids.

Now the operation will be described as for cooling milk. With the parts as in the solid lines of the drawings, milk flows downward as indicated by the arrows of Fig. 9 first through the pipe 63 and then through the pipes 66 (Fig. 8) and perforations thereof, thereby to be evenly supplied all along the upper ends of the passages 52. In passages 52 the thin stream of milk passes back and forth to the lower header chamber 25 (Fig. 3) and 15 cut at the discharge conduit 69 (Fig. 6).

At the same time the cold brine passes upwardly in the lower supply pipe 70 (Fig. 3) and then through the lower branch pipes 73, 77 into the lower part of the chamber of housing 23, and 20 chamber 40, where it flows upwardly around the ends of the baffles 93, 94 (Figs. 6 and 9) and finally out and upwardly through the upper pipes 73, 77 and 71.

When it is desired to clean the apparatus, the 25 flow of liquid from the pipes 63, 69, 70, 71, is cut off by means not shown and the chambers drained. Then the nuts 58 and 85 are loosened, the clamping means 56 and 88 are moved to the 30 position of the middle and upper part of Fig. 4, whereupon the outer chambers 40 may be moved, as indicated by the dot and dash lines of Fig. 6, and then to a position entirely away from the inner chamber. Then the parts 64, 65, 66, 67 (Fig. 8) can be disassembled.

35 This will make all of the milk receiving surfaces easily accessible for cleaning and sterilizing, after which the parts may be reassembled.

I claim as my invention:

1. In combination, a frame comprising upper, 40 lower and upright members having outwardly directed flanges; a horizontal inner flow chamber, for temperature exchanging medium, secured to and between the upright members and spaced from the other members to form inlet and outlet header chambers and said horizontal chamber comprising top and bottom walls, parallel upright end walls secured to the upright members, and side walls of deeply meandering cross-section cooperating with the end walls to form laterally projecting chamber portions; outer flow chambers having top, bottom, side and end walls, the end walls marginally projecting beyond the other walls to form end flanges; said latter flanges adapted to be secured to adjacent respective flanges of said frame; the flanged margins of the top and bottom walls being outwardly offset adjacent to the flange to form inner seats; the outer chamber comprising an inner heat-exchanging wall having inwardly turned upper and lower flanges seated on said seats, the part between said flanges having a deeply meandering cross section cooperating as to height with the end walls to form deep inwardly tapering recesses adapted to receive said projections to form a passage space; 55 the outer flanges of the frame and outer chambers serving as projection and anchorage for heat-insulating material secured on the web and outer walls.

2. In combination, a frame comprising upper, 70 lower and upright channel members forming webs; an inner chamber secured to the upright members, and spaced from the other members to form header chambers, said inner chamber comprising side walls of meandering cross-section to form laterally projecting chamber portions; outer

flow chambers connected fluid-tight on each side of said frame; each outer chamber having an inner wall cooperating with said projections to form a thin meandering passage space connecting said header chambers; liquid inlet and discharge 5 means connected to the inner chamber and detachably connected to the outer chambers; a liquid supply pipe passing in a fluid-tight manner through the upper web of the frame and clamped to the web by a ring nut, and provided at its inner end with a T-connection; perforated distributing pipes having detachable-plug-closed outer ends secured in the connection and disposed along the header chamber to distribute liquid passing in through the supply pipe; and a discharge pipe 10 passing through the mid part of the lower web, whereby a stream of the liquid may be kept passing through said passage space.

3. In combination, a frame comprising upper, 20 lower and upright members; an inner chamber secured to the upright members, and spaced from the upper and lower members to form header chambers and comprising side walls; outer flow chambers connected fluid-tight on each side of said frame; each outer chamber having an inner 25 wall cooperating with said side walls respectively to form thin passages connecting said header chambers; and liquid supply and discharge means for the chambers respectively.

4. In combination, a frame comprising upper, 30 lower and upright members having outwardly directed flanges on each side; an inner chamber secured to the upright members, and spaced from the upper and lower members to form header chambers; said inner chamber comprising side 35 walls; outer flow chambers having flanges detachably connected on each side of said frame; each outer chamber having an inner wall cooperating with the side walls respectively so as to form thin passages connecting said header chambers; and liquid supply and discharge means for the 40 chambers respectively.

5. In combination, a frame comprising upper, 45 lower and upright members each having outwardly directed flanges; an inner chamber secured to the upright members, and spaced from the other members to form header chambers, said inner chamber comprising side walls; outer flow chambers connected fluid-tight on each side of said frame and comprising flanges engaged 50 with said flanges of the frame; each outer chamber having an inner wall spaced from said side walls to form a passage connecting said header chambers; liquid supply and discharge means for the header chambers respectively; a discharge 55 means passing from the lower header chamber; liquid inlet and discharge means for the inner chamber and outer chambers; H-blocks pivoted at one end between flanges of the frame and each having an outer transverse bore; clamping bolts in said bore and provided with heads and wing-nuts; adjacent flanges of said frame and outer chambers being provided with deep bolt receiving notches, gaskets between the adjacent flanges, 60 said notches adapted to receive said bolts whereby the adjacent flanges and gaskets may be clamped together in a fluid tight manner.

6. In combination, a frame comprising upper, 70 lower and upright members; an inner chamber secured to the upright members, and spaced from the other member to form header chambers, said inner chamber comprising side walls of deeply meandering cross-section to form laterally projecting chamber portions; movable supports; relatively movable outer chambers mounted on 75

said supports and connected fluid-tight on each side of said frame; each outer chamber having an inner wall of meandering cross-section to form deep inwardly tapering recesses adapted to receive said projections to form a thin meandering passage connecting said header chambers; an inlet having distributing supply means disposed along the upper header chamber; a discharge means passing from the lower header chamber; inlet and discharge pipes having connectors secured thereto; branch pipes extending from the respective connectors to the upper and lower portions of the inner chamber; and movable branch pipes extending from the upper and lower end parts of the outer chambers and detachably secured to the adjacent connectors.

7. In combination, an inner temperature exchanging chamber; a pair of temperature changing chambers detachably connected to the inner chamber, said chambers having side walls of deeply meandering cross-section cooperating to form a thin passage space, fluid inlet and outlets for the top and bottom of said passage, and inlet and discharge pipes extending to near different parts of said chambers respectively; a 4-way connector on each pipe communicating with the inner chamber; each connector having oppositely disposed horizontal members each provided with an end seat face; movable branch pipes extending through the upper and lower parts of the outer chamber to near the respective end seats and having free ends adapted to be received in said seats; a clamping collar secured on each free end portion; a thick rubber gasket ring disposed between the collar and adjacent seat; a bracket on each 4-way connector each having a bore parallel to the horizontal members; a clamping bolt in said bore having a wing head at one end and threads at the other; and clamping jaws on said bolt and engaged by the threads and head and provided with lateral recesses adapted to receive the pipes to hold the jaws in engagement with said collars whereby the collars, gaskets and seats may be held together in a fluid tight manner.

8. In combination, a pair of supports one of the supports being movable relative to the other; a pair of temperature exchanging chambers detachably connected to each other, and mounted on said supports, said members having adjacent side walls cooperating to form a thin meandering passage; fluid inlets and outlets for said chambers, and milk supply and discharge means communicating with opposite parts of said passage.

9. In combination, a pair of supports; wheels on one of the supports; tracks for said wheels extending transverse to the supports; a pair of temperature exchanging chambers detachably connected to each other, and mounted on said supports, the chambers having adjacent side walls cooperating to form a thin passage space; supply and discharge means communicating with opposite parts of said space; and liquid inlet and discharge means for said chambers, being detachably connected to one of them.

10. In combination, an elongated inner pedestal support having feet and flat supporting heads at the ends; an elongated rectangular frame supported in a vertical plane and comprising upper, lower and upright members consisting each of a web perpendicular to said plane and flanges on opposite edges of the web extended in a direction away from the interior of the frame, said heads being received between the flanges and against the web of the lower frame member; an inner chamber secured to the upright members, and spaced from the other members to form header chambers, said inner chamber comprising side walls of meandering cross-section to form laterally projecting chamber portions; a pair of elongated movable supports having wheels mounting them for lateral movement; tracks for said wheels guiding the movable supports into parallel cooperation with the inner support; an outer flow chamber having a section mounted on each outer support and connected detachably and fluid-tightly on each side of said frame; each outer section having an inner wall of meandering cross-section to form recesses adapted to receive said projections and to form a thin meandering passage connecting said header chambers; and liquid supply and discharge means for the chambers respectively.

11. In combination, a frame including a band or web, a chamber disposed within said band and spaced therefrom, said chamber having side extensions; an outer chamber having sections cooperating with said extensions and spaced therefrom, said sections having their inner ends engaged against the sides of said frame, and said spaces providing a continuous passage; top and bottom inlet and outlet means disposed in said band and communicating with said passage whereby fluid may be moved downwardly therethrough, and tubular means communicating with the bottoms and tops of the respective chambers, whereby to move fluid upwardly, the tubes of said inner chamber being passed through said band so as to support said inner chamber.

12. In combination, a rectangular frame including a web, a chamber disposed within said frame in spaced relation therewith and having a practically flat top, said chamber having side extensions; an outer chamber having sections cooperating with said extensions and spaced therefrom to form a passage, said sections having their inner ends engaged against said frame; tubular means passing through said web to and from the bottom and top of said inner chamber whereby to support the latter; tubular means passing into and out of the bottom and top of said sections; said means adapted to control upward movement of liquid through said chambers; liquid inlet and outlet means disposed in the top and bottom portions of said web and being in communication with said passage, and means carried by said inlet means for distributing liquid over said flat top and downwardly through said passage.
